UNITED STATES PATENT OFFICE.

BERRY A. BAXTER, OF MANSFIELD, OHIO, ASSIGNOR TO NEW METHOD STOVE COMPANY, OF MANSFIELD, OHIO, A PARTNERSHIP COMPOSED OF HENRY H. SANFORD, BERNHARD R. AHRENDT, EDWIN D. BAXTER, AND BERRY A. BAXTER.

GAS-RANGE.

1,118,622.

Specification of Letters Patent.

Patented Nov. 24, 1914.

Application filed June 6, 1914. Serial No. 843,433.

To all whom it may concern:

Be it known that I, BERRY A. BAXTER, a citizen of the United States of America, residing at Mansfield, in the county of Rich-
5 land and State of Ohio, have invented cer-
tain new and useful Improvements in Gas-
Ranges, of which the following is a specifi-
cation.

This invention relates to certain new and
10 useful improvements in gas ranges, and the
primary object thereof is to provide an
improved structure in which the oven may
be formed of desired size and secured to the
body of the range so as to leave the cooking
15 or heating surface of the range free and un-
obstructed so as to not interfere with free
use of such surface.

The invention further has for its object
to provide improved means for rigidly and
20 economically securing the oven in position
on the body of the range while still main-
taining the cooking or heating surface free
of obstructions.

Further and other objects will be later
25 set forth and of themselves manifested in
the course of the following description.

In the drawings, Figure 1 is a front per-
spective view of the invention; Fig. 2 is an
30 end elevation; Fig. 3 is a top plan view,
partly broken away; and Fig. 4 is a detail
view, partly in section and in side elevation,
showing the manner of supporting the front
side of the oven.

In proceeding in accordance with the pres-
35 ent invention, an oven 1 of desired length
and width is mounted above the range body
2 in such manner that the back of the oven
projects beyond the top plate 3 of the range
40 body 2 as depicted in Figs. 2 and 3 of the
drawings, the object of which is to leave a
larger amount of room at the front of the
top plate 3. The oven is supported at its
45 rear side by a pair of similar brackets 4
which brackets have vertical bodies 5 the
upper ends of which are provided with lugs
6 upon which latter the bottom of the oven
1 rests and is secured by screws or bolts 7.
The lower ends of the bodies 5 are provided
50 with intermediate inclined seats 8 which are
secured by bolts 9 to the rear side of the top
plate 3. The lower ends of the brackets are
offset or incline inwardly at 10 and have
feet 11 which are secured by screws or bolts
55 12 to the back wall of the range body. The

front side of the oven is supported by means
of a horizontal gas supply pipe 13 which is
connected by an end vertical pipe 14 to the
top plate 2. Brackets 15 are secured by
screws 16 to the under side of the oven 1
and are formed with curved fingers 17 which
60 rest on the supply pipe 13 whereby the oven
is secured against downward movement at
its front side.

To further secure the oven in position and
against vibration, a back wall 18 is secured
65 to the body 2 and is provided with a canopy
top 19, the back wall and canopy being se-
cured to the inner end of the oven structure
1 so as to brace the latter and hold same in
rigid position.

It is particularly to be noted that the
brackets are rigidly braced, since they are
secured at their lower ends and at points
between their ends to the range body, and
since there is but one pipe 14 employed
75 which is located at one of the ends of the top
plate 2 it will be seen that the entire sur-
face of the top is completely free of any ob-
structions, which enables any part of the
cooking or heating surface to be freely used.

It will be seen from the above that the
oven is effectively secured at both sides and
ends thereof and is held against vibration
accordingly.

The top is preferably provided with a rec-
85 tangular plate 20 which is used as a means
for heating irons.

What is claimed is:

1. In a gas range, in combination with the
range body, an oven disposed above the top
90 plate of the body and having its back pro-
jecting beyond the back of the body, leav-
ing a part of the top plate extending in
front of the oven and the space above said
part clear and unobstructed, a pair of brack-
95 etts having horizontal lugs on their upper
ends secured to the oven bottom and having
seats between their ends secured to the top
plate of the body, said brackets having off-
set lower ends provided with vertical feet
100 secured to the back of the body, a vertical
member connected at its lower end to the
top plate and disposed at the outer end of
the top plate and the outer end of the oven,
a horizontal member connected to the upper
105 end of the vertical member and disposed at
the front side of the oven, and a plurality
of brackets connected to the oven bottom and

having hook-shape front ends which rest upon the horizontal member.

2. In a gas range, in combination with the range body, an oven disposed above the top plate of the body and having its back projecting beyond the back of the body, leaving a part of the top plate extending in front of the oven and the space above said part clear and unobstructed, a pair of brackets having upper portions connected to the projecting part of the oven, intermediate portions secured to the top plate and lower portions secured to the back of the body, a vertical member connected to the top plate and located at the outer end of the latter and at the outer end of the oven, a horizontal member connected to the vertical member and disposed at the oven front side, a series of brackets connected to the front side of the oven and engaged with said horizontal member, a back wall on the body and a canopy on the back wall, the back wall and canopy being each connected to the inner end of the oven.

3. In a gas range, in combination with the range body, an oven disposed above the top plate of the body and having its back projecting beyond the back of the body, leaving a part of the top plate extending in front of the oven and the space above said part clear and unobstructed, a pair of brackets having upper portions connected to the projecting part of the oven, intermediate portions secured to the top plate and lower portions secured to the back of the body, a vertical

member connected to the top plate and located at the outer end of the latter and at the outer end of the oven, a horizontal member connected to the vertical member and disposed at the oven front side, a series of brackets connected to the front side of the oven and engaged with said horizontal member, a back wall on the body and a canopy on the back wall, the back wall and canopy being each connected to the inner end of the oven.

4. In combination with the body of a gas range, a superposed oven having its back wall extended beyond the back of the body, leaving a part of the top plate extending in front of the oven and the space above said part clear and unobstructed, means located in the rear side of the range body to secure the rear side of the oven to the body, means disposed in part at the outer end of the oven and across the front side thereof at the oven bottom to secure the front side of the oven, and a back wall on the body secured to the inner end of the oven and to the oven bottoms at points between the front and rear sides of the oven.
